UNITED STATES PATENT OFFICE.

JOHN ZIMMERMANN, OF PHILADELPHIA, PENNSYLVANIA.

WARP-PRINTING MACHINE.

1,195,322.

Specification of Letters Patent. Patented Aug. 22, 1916.

Application filed September 1, 1915. Serial No. 43,377.

To all whom it may concern:

Be it known that I, JOHN ZIMMERMANN, of Philadelphia, in the county of Philadelphia and State of Pennsylvania, have invented certain new and useful Improvements in Warp-Printing Machines, whereof the following is a specification, reference being had to the accompanying drawings.

The invention relates to new and useful improvements in warp printing machines wherein the coloring matter is applied to the warp threads by pattern-controlled mechanism.

An object of the invention is to provide a machine of the above character with devices whereby the warp threads as they pass continuously through the machine, may be supplied uniformly with coloring matter in accordance with a predetermined pattern.

20 A further object of the invention is to provide a printing device for a warp thread machine of the above character wherein the printing rolls are partly submerged in the coloring matter and wherein a device is pro-

25 vided for evenly distributing the coloring matter on the surface of each printing roll, said device being so constructed as to maintain a uniform surface of coloring matter regardless of any inequality in the surface

30 of the said printing rolls.

A further object of the invention is to provide a printing device of the above character, wherein the warp threads are continuously passed through the printing device, 35 and the different colors applied simultaneously, with means for setting the printing color in the warp threads, together with devices for washing the sizing and surplus color from the threads, and subsequently

40 drying the same.

These and other objects will in part be obvious, and will in part be hereinafter more fully disclosed.

In the drawings, which show by way of 45 illustration one embodiment of the invention: Figure I is a side elevation of an apparatus having my improvements applied thereto; Fig. II is an enlarged side view of a portion of the printing device; Fig. III 50 is a detail showing in section one of the printing rolls and the means for causing the thread to engage the same; Fig. IV is a view in section showing one end of the drying chamber and the means for washing the

thread; and Fig. V is a bottom plan view 55 of one of the color distributing devices.

The invention consists generally in providing a supporting frame on which the beam containing the warp threads to be colored are mounted. The warp threads are 60 led from this beam through a printing device wherein printing rolls, partly submerged in coloring matter, are caused by a pattern controlled mechanism to be engaged by the threads, thus producing in colors on 65 the threads, predetermined patterns, after which said threads are passed through a steaming chamber where the colors are set and from the steaming chamber the threads are led through a washing apparatus which 70 removes the sizing and surplus dye from the threads. After leaving the washing apparatus, the surface water clinging to the threads is stripped therefrom pneumatically, after which the threads are led through a 75 drying chamber. The threads are passed continuously through these several devices and are finally wound on suitable beams.

The printing devices for the threads consist of a series of printing rolls each of 80 which runs in a color box so that the rolls are partly submerged in the coloring matter. A distributing device coöperates with each printing roll to maintain a uniform coating or layer of the coloring matter on a 85 roll at the region where the threads are brought into contact with the rolls.

The washing apparatus consists of a plurality of trays over which the threads are led and intermittently operated arms which 90 immerse the threads in the water contained in the trays as they move along over the same. The surface water clinging to the threads is stripped therefrom by jets of air located in the path of travel between the 95 washing apparatus and the drying chamber.

Referring more in detail to the drawings, the improved apparatus consists of a supporting frame 1, on which is mounted a shaft 2 carrying the supporting beam 3 for 100 the threads to be printed, which threads are indicated at 4. This supporting frame 1 is connected to the frame 4 of the printing device.

The warp threads pass over suitable tension rolls 5 and 6 mounted in the frame 4 of the printing apparatus and then around a feed roll 7. This feed roll is intermittently

operated by a pawl and ratchet mechanism 8. The pawl is carried by a swinging rock arm 9 which may be operated in any suitable way. It is understood that the warp threads 5 pass side by side over the feed roll 7.

As herein shown, the printing apparatus includes a series of color boxes 10 which are mounted on a carriage 11 having supporting wheels 12 adapted to run on tracks 13. 10 These tracks are so disposed that the carriage may be run underneath the supporting frame 4 of the printing apparatus and the printing rolls properly positioned beneath the warp threads. Each color box 10 15 is provided with a color roll 14 which is mounted in suitable bearings in the box. This printing roll is preferably formed with a continuous printing pad covering 15 which may be of any desired character. The roll 20 is mounted so that it runs partly submerged in the coloring matter which is indicated at 16 in Fig. III of the drawings. Each of these color boxes may be supplied with a different coloring matter and each printing 25 roll extends the full width of the printing frame so as to be located directly underneath all of the warp threads passing through the printing apparatus.

The supporting rolls for the warp threads 30 at the leading-in side of the printing apparatus and the guide roll 17 at the other side of the apparatus, are so positioned relative to the carriage supporting the coloring boxes and the printing rolls that the normal path 35 of travel of the threads through the printing apparatus is slightly above the surface of the printing rolls, as clearly shown in Figs. II and III.

Coöperating with each printing roll is a 40 series of impression members 18. There is an impression member for each line of warp threads passing over the printing rolls and there is an impression member located above each thread for each printing roll. As shown 45 in Fig. II of the drawing there are eight series of impression members and coöperating with these eight series of impression members are eight printing rolls, each of which runs in a separate color box as above 50 noted. These impression members, as shown in the drawings are arranged so as to be moved vertically by supporting cords 19 actuated by a suitable jacquard pattern mechanism. This pattern mechanism operates to lower the impression members in 55 accordance with the pattern desired. When the impression member is lowered it drops upon the warp thread and forces the same down into contact with the surface of the 60 printing roll directly underneath the lowered impression member. When an impression member is lowered so as to bring the warp thread into contact with the printing roll, said thread will be coated or printed 65 with the coloring matter of the roll with

which it makes contact. By lowering the various impression members, it will be readily seen that the threads may be printed in different colors simultaneously or in succession and in accordance with the pattern desired. 70

In order that a uniform coating or layer of coloring matter may be maintained upon the surface of the printing rolls, each roll is provided with a distributing device or 75 evener. This evener comprises a plurality of sections 20, which extend from end to end of the printing roll and are pivotally supported by brackets 21 attached to the color box. These eveners on their under 80 faces are formed with projecting ribs 22 and said evener sections bear by gravity upon the surface of the printing roll. The height of these ribs determines the thickness of the layer of coloring matter permitted to remain on the surface of the printing roll. As the roll rotates in the direction of the arrow in Fig. III, the lower edge of the evener will scrape off all the coloring matter, except that which passes underneath the 85 same and is thus distributed in a uniform layer of coloring matter throughout the entire length of the printing roll. If there should be slightly uneven places in the surface of the roll, inasmuch as the evener comprises several sections and extends from end to end thereof and has a straight edge underface, the surface of the coating material left on the coating roll will be smooth and without irregularities. By the above 90 construction of the distributing device, the printing rolls may be caused to rotate directly in the coloring matter and an even coating of coloring matter supplied to the warp threads. It will be understood that 95 each printing roll is provided with a separate distributing device. The printing rolls are intermittently rotated by suitable intermeshing gears mounted on the ends of the rollers and these gears may be driven from 100 the feeding roll 7, through an intermediate gear 23. It will be understood of course, that adjacent printing rolls are rotated in opposite directions as each printing roll is 105 geared to its adjacent fellow. 110

The distributing devices are positioned relative to the direction of rotation of the printing rolls so as to engage the coloring matter on the printing rolls before the printing rolls come into contact with the warp 115 threads. 120

After leaving the printing apparatus, it is desired to pass the warp threads with the coloring matter thereon to a steaming chamber so that the coloring matter may be 125 set in the threads. In Fig. I of the drawings, I have shown a steaming chamber 24. The warp threads after passing over the guiding roller 17 are led over a guiding roller 25 carried by a bracket attached to 130

the outer wall of the steaming chamber and are then led into the steaming chamber, the threads running back and forth horizontally over the guiding rolls 26 at the opposite ends 5 of the steaming chamber. Said steaming chamber is supplied with steam through the piping 27.

The threads after leaving the steaming chamber pass over a guiding roller 28 and 10 thence through a washing apparatus. This washing apparatus consists of a series of pans 29 and the threads pass over these pans and about a guiding roller 30 at the other end of the main frame of the apparatus.

15 These pans are kept supplied with a continuous flow of water through a pipe 31 which discharges into each of the pans and the overflow from the pans is received by the trough 32 which extends underneath the 20 pans.

Associated with each pan is a cross shaft 33 carrying oppositely extending arms 34 and 35. These arms carry paddles 36 which extend from side to side of the apparatus.

25 The arms are oscillated by means of links 37 which coöperate with suitable eccentrics 38 on the driving shaft 39, see Fig. IV. As the arms are oscillated, first the paddle carried by the arms 34 will engage the threads 30 and immerse the same in the water in the pans and then the paddle carried by the arms 35 will engage the threads and direct their course beneath the surface of the water so that they are immersed. It will be

35 understood that although the threads are traveling continuously over the pans their course of travel will be constantly changed so that they are immersed beneath the surface of the water in one region and then another and this greatly facilitates the thorough washing of the threads. In employing a series of independent trays in the washing apparatus a more thorough washing may be obtained since the dyes and sizing eliminated in one tray cannot be carried into the next.

40 After passing through the washing pans, the threads are subjected to a blast of air from pipe 40. The jets of air from the pipe 50 on to the threads strip the water from the surface of the threads. The water stripped from the threads at this point is caught in the trough 32.

The threads after leaving the guiding roll 55 30 are carried through a drying chamber 41 and led over rollers 42—42 at the opposite ends of the drying chamber. Pipe coils 43 extend across the drying chamber and serve as a heating means to assist in drying the 60 warp threads. After leaving the drying chamber, the threads are led over guiding feed rollers 44, thence over suitable guiding rolls 45 and 46, after which the warp threads are rewound on beams 47.

65 From the above description it will be ap-

parent that the warp threads are passed through a printing device where they are uniformly printed in accordance with any desired pattern, after which they are passed to a steaming chamber wherein the coloring matter is set in the threads and thence the threads are led to a washing device for removing the sizing and the surplus coloring matter. The water clinging to the threads is removed to a large extent by jets of air 70 playing on the same and finally the threads are dried and rewound for use in the looms. It is obvious that the warp thread above referred to may consist of one or more warp threads.

75 It is also obvious that minor changes in the details of construction and arrangement of parts may be made without departing from the spirit of the invention as set forth in the appended claims.

80 Having thus described my invention, I claim,

1. A warp thread printing machine, including in combination a printing roll having a continuous printing surface, means 90 for supporting coloring matter in contact with the lower surface of the printing roll, means for evenly distributing said coloring matter on the surface of said roll, means for guiding a plurality of warp threads in a 95 path normally above the printing roll and pattern controlled impression members for causing the warp threads to contact with the printing roll.

2. A warp thread printing machine, including in combination a series of printing rolls, a color box for each roll, means for supporting the rolls whereby the same are partly immersed in the coloring matter, a device coöperating with each printing roll 100 for evenly distributing the coloring matter on the upper surface of the roll, means for guiding a plurality of warp threads in a path normally above the printing rolls, said threads extending transversely across the 105 same and pattern controlled impression members for causing the warp threads to contact with any one of the printing rolls.

3. A warp thread printing machine, including in combination, a printing roll having a continuous printing surface, means for supporting coloring matter in contact with the lower part of said printing roll, a distributing device including a member extending lengthwise of the roll and having 115 means for holding said member spaced from the surface thereof, means for guiding a plurality of warp threads in a path normally above the printing roll, and pattern controlled devices for causing said threads 120 to contact with the printing roll.

4. A warp thread printing machine, including in combination a printing roll having a continuous printing surface, a color box for said roll, means for supporting the 130

roll so that the lower part thereof only is immersed in the coloring matter, a distributing device including a member extending lengthwise of the roll, transverse ribs mounted on the lower face of said member and adapted to engage the roll and hold said member a predetermined distance from the surface of the roll, means for guiding a plurality of warp threads in a path normally above the printing roll and pattern controlled devices for causing said threads to contact with the printing roll.

5. A warp thread machine including in combination a plurality of printing rolls arranged side by side, a color box for each roll, means for supporting the rolls whereby each is partly immersed in the coloring matter in its respective box, means for connecting the printing rolls whereby they are simultaneously rotated, a distributing device for each roll, said distributing device including a member extending from end to end of the roll and having ribs on its lower surface engaging the surface of the roll whereby said member is held a predetermined distance from the surface of the roll, means for guiding a plurality of warp threads transversely across the rolls in paths normally above said roll and pattern controlled devices for causing said threads to contact with any one of said rolls.

6. A warp thread printing machine including in combination a printing apparatus comprising printing rolls, and devices for causing the warp threads to engage the printing rolls, a series of washing pans over which the threads are directed, intermittently operated arms normally disposed over said threads and movable into engagement with the threads for immersing the threads in said pans, and a drying chamber for receiving the threads after they leave the washing pans.

7. A warp thread printing machine including in combination a printing apparatus comprising printing rolls, and devices for causing the warp threads to engage the printing rolls, a series of washing pans over which the threads are directed, intermittently operated arms normally disposed over said threads and movable into engagement with the threads for immersing the threads in said pans, means for directing a blast of air against the threads for stripping the surface water therefrom, and a drying chamber for receiving the threads after they leave the stripping means.

8. A warp thread printing machine including in combination, a printing apparatus comprising printing rolls and devices

for causing the warp threads to engage the printing rolls, a steaming chamber for receiving the warp threads after leaving the printing rolls, a series of washing pans over which the threads are directed, intermittently operated means for immersing the threads in said pans and a drying chamber for receiving the threads after they leave the washing pans.

9. A warp thread printing machine including in combination, a printing apparatus comprising printing rolls and devices for causing the warp threads to engage the printing rolls, a steaming chamber for receiving the threads after they leave the printing rolls, a plurality of washing pans over which the threads are directed, intermittently operated arms for engaging the threads adjacent one end of said pans and then the other and moving the same beneath the surface of the water, means for directing a blast of air against the threads for stripping the surface water therefrom and a drying chamber for receiving the threads after they pass said stripping means.

10. A warp thread printing machine including in combination a printing apparatus comprising printing rolls, devices for causing the warp threads to engage the printing rolls, a steaming chamber for receiving the warp threads after leaving the printing rolls, a series of separate washing pans over which the threads are directed in succession, intermittently operated devices disposed over said threads and movable into engagement with the threads for immersing the threads in said pans, and a drying chamber for receiving the threads after they leave the washing pans.

11. A warp thread printing machine including in combination a printing apparatus comprising printing rolls, devices for causing the warp threads to engage the printing rolls, a steaming chamber for receiving the warp threads after leaving the printing rolls, means for washing the threads after passing through the steaming chamber, means for directing a blast of air against the threads for stripping the surface water therefrom, and a drying chamber for receiving the threads after they pass the stripping means.

In testimony whereof, I have hereunto signed my name, at Philadelphia, Pennsylvania, this twenty-fifth day of August 1915.

JOHN ZIMMERMANN.
